UNITED STATES PATENT OFFICE

142,472

DESIGN FOR A VEGETABLE CUTTER

Frederick W. Eames, Medford, Mass.

Application April 12, 1945, Serial No. 118,968

Term of patent 7 years

(Cl. D89—1)

To all whom it may concern:

Be it known that I, Frederick W. Eames, a citizen of the United States, residing at Medford, in the county of Middlesex and Commonwealth of Massachusetts, have invented a new, original, and ornamental Design for Vegetable Cutter of which the following is a specification, reference being had to the accompanying drawings, forming part thereof.

In the drawings,

Fig. 2 is a plan view of the vegetable cutter; and

Fig. 3 is a front elevation of the vegetable cutter, the handle being fragmentarily shown for convenience of illustration.

I claim:

The ornamental design for a vegetable cutter, substantially as shown and described.

FREDERICK W. EAMES.
